UNITED STATES PATENT OFFICE.

JOSEPH C. FIELD, OF ORANGE, NEW JERSEY, ASSIGNOR TO WESTERN ELECTRIC COMPANY, INCORPORATED, OF NEW YORK, N. Y., A CORPORATION OF NEW YORK.

IMPULSE-TRANSMITTER.

1,306,054.

Specification of Letters Patent. Patented June 10, 1919.

Application filed May 10, 1916. Serial No. 96,503.

To all whom it may concern:

Be it known that I, JOSEPH C. FIELD, a citizen of the United States, residing at Orange, in the county of Essex and State of New Jersey, have invented certain new and useful Improvements in Impulse-Transmitters, of which the following is a full, clear, concise, and exact description.

This invention relates to impulse transmitters for use in connection with party line or like systems wherein there are a plurality of subscriber or way stations on the same line, each station being provided with a selector mechanism adapted in response to impulses sent over the line to close a signaling circuit at that station, the number of impulses for calling the stations being different for each particular selector.

This invention has for its object the provision of an impulse transmitter which will be compact, sure and quiet in its operation, easily manufactured and one which can be easily and speedily adjusted to transmit the proper combination of impulses for calling any particular station on the line.

The impulse transmitter to which this invention relates comprises, in general, a clock-work mechanism in which energy is stored up by the turning of a handle which winds a spring. When the handle is released, the spring revolves a shaft upon which is mounted a toothed wheel, adapted to operate contact springs to make and break a circuit. Two adjustable cam members are provided for covering up certain of the teeth to permit of the transmitting of any desired combination of impulses. These cam members, and the other operating parts of the impulse transmitter, are so related that one cam serves to hold the contact springs engaged, and the other to hold the contact springs disengaged for definite periods of time.

In the drawings illustrating this invention, Figure 1 is a side elevation of the impulse transmitter;

Fig. 2 is a view of the back end of the impulse transmitter;

Figs. 3, 4 and 5 show the toothed wheel, cam members and contact springs in normal position, the cam members being set in different positions to give different combinations of effective teeth; and

Figs. 6, 7 and 8 are detail views illustrating the different positions assumed by the

contact springs in the rotation of the toothed wheel.

Referring to the drawings, 5 and 6 designate frame plate members secured together by rods 7, 8 and 9. Supported in these frame plates 5 and 6 are shafts 10 and 11, the shaft 10 constituting a driving and the shaft 11 the driven shafts of the mechanism. Loosely mounted upon the shaft 10 is a gear wheel 14, adapted to be driven by a spiral spring 15 on said shaft. Gear wheel 14 meshes with a pinion 16 on the shaft 11, which pinion is secured to a gear wheel 17, also on the shaft 11, gear wheel 17 being in mesh with a pinion 18, loosely mounted upon the shaft 10 and secured to a gear wheel 19. The gear wheel 19, in turn, meshes with a pinion 20, loosely mounted upon the shaft 11 and secured to a gear wheel 21. The gear wheel 21 meshes with a worm on a governor shaft 22, which is arranged at right angles to the shafts 10 and 11, and supported between arms 23, 23, formed integrally with the plate 6. The governor consists of two weighted spring arms 24 and 25, which, as the governor shaft 22 is rotated, are caused to throw the weights outwardly against the inner face of a metal drum 26, the friction of the weights and drum tending to retard the movement of the rotating parts and keep them at a constant speed.

The transmitting device of this invention is designed particularly for use in connection with circuits and apparatus similar to that shown in my copending application, Serial No. 98,384, filed May 16, 1916. In this application there is disclosed a system in which selectively-operated circuit-closing devices are adapted to be conditioned for operation in response to a combination of alternating current impulses of long and short duration, the impulses of short duration being adapted to advance a step-by-step element, while the impulses of longer duration serve to hold the step-by-step element in an advanced position, or cause its release, as the case may be. A pole-changing relay is provided which is controlled through contact springs on the impulse transmitter to connect current of one polarity or the other with the line circuit. When the contact springs are in engagement with each other, current of one polarity is maintained on the line, and when the contact springs are out of engagement with each other and the impulse wheel is

rotating, current of the opposite polarity is maintained on the line.

The specific arrangement of parts whereby the circuits are controlled to cause impulses 5 to be sent out on the line is as follows:

- Mounted upon the inner end of the shaft 11 beyond the frame plate 6 is a wheel or disk 30, having formed on the larger portion of its periphery, a plurality of teeth 31, 31, 10 which are adapted to coöperate with spring contacts 32 and 33 to alternately make and break a circuit including these contacts. As shown, the wheel 30 is provided with a cut-away portion 34, in which the free end of 15 spring 32 is normally positioned out of engagement with the wheel 30. Contact spring 32 is in electrical contact with the wheel 30 during the entire time this wheel is making a complete revolution. The wheel 30 is also 20 provided with portions 35 and 36 which are free from teeth, their radii being the same as the radius of the wheel 30 at the base of the teeth 31, 31. When contact 32 is in engagement with the portion 35, a circuit is closed 25 for sending over the line a long impulse of current to insure the return to normal position of all selectors on the line before the stepping operation begins. When contact 32 engages the portion 36, a long impulse is 30 sent over the line to return to normal position the selector at the called station. The portion 37 provided on wheel 30, which has the same radius as the outer face of the teeth 31, 31, controls the duration of the 35 operation of the signaling device at the selected station. As the spring contact 32 rides on top of a tooth, a short impulse of one polarity is sent over the line, and when the spring contact 32 is between two teeth, a 40 short impulse of the opposite polarity is sent over the line, as set forth in the hereinbefore noted co-pending application. The number of effective teeth which pass under contact spring 32 is determined by means of adjustable plates or cam members 38 and 39, pivotally mounted upon the end of shaft 11 in juxtaposition to the toothed wheel 30, each cam member being provided with an articulated slot 40, concentric with the shaft 11. A 45 screw 41, passing through the slots into the face of the toothed wheel, is adapted to secure the cam members 38 and 39 in any adjusted position. The periphery of each cam member preferably extends slightly beyond 50 the outer faces of the teeth 31, 31. The body of cam member 38 is substantially parallel to wheel 30, as shown in Fig. 1, and the periphery thereof is adapted, in the rotation of the wheel 30, to engage the free end of contact spring 32 to raise said spring, and maintain it in engagement with contact spring 33 for a considerable length of time as compared with the engagement of these contact springs caused by a single tooth (see Fig. 8). 55 The cam member 39 is formed so that the

periphery thereof is separated from the wheel 30 (see Figs. 1 and 7) and the periphery thereof is adapted, in the rotation of the wheel 30, to engage an insulating roller 45, mounted in a projection 46 on the free end of contact spring 33 to raise this contact spring 33, and maintain it out of engagement with contact spring 32 for a considerable length of time (see Fig. 7). It will be noted that the periphery of cam member 38 does not 75 engage the insulating roller 45, and that the periphery of cam member 39 does not engage the end of contact spring 32.

The toothed wheel 30 is adapted to make one complete revolution each time a call is 80 made, and in this connection is provided on one face with a projecting stop lug 50, adapted to engage a movable stop lug 51, carried by the shaft 10. In the operation of these particular parts, the shaft 10 is turned 85 by a handle 52 until the stop lug 51 comes into contact with a stop pin 53, projecting from the frame plate 6. When the handle is released, the two shafts 10 and 11 travel at such relative speed that the wheel 30 is 90 caused to make a complete revolution while the stop lug 51 is moving back into position to engage stop pin 50 on said wheel. The shaft 10 projects through a mounting plate 54 so that the handle 52, thereon, may be 95 easily manipulated from the front of the transmitter.

The contact springs 32 and 33 are mounted upon a supporting lug 60, formed integrally with the frame plate 6, the contact springs 100 being insulated from each other and the frame. The supporting lug 60 also supports two contact lugs 61 and 62, insulated from the frame and in electrical connection with the contact springs 32 and 33, respectively. 105

What is claimed is:

1. In an impulse transmitter, a rotatable toothed wheel, contact springs brought into and out of engagement by the teeth of said wheel, an insulated roller carried by one of said contact springs, a cam segment carried by said wheel for maintaining the contact springs in engagement during a portion of the travel of said wheel, and another cam segment carried by said wheel and engaging 110 said insulated roller during a portion of the travel of said wheel for maintaining said contact springs out of engagement.

2. In an impulse transmitter, a rotatable toothed wheel, a contact spring normally 115 insulated from said wheel while said wheel is at rest but in electrical contact therewith during a complete revolution thereof, a second contact spring with which the first contact spring is brought into and out of engagement by the teeth on said wheel, and cam segments carried by said wheel for maintaining the contact springs in engagement during a portion of the travel of said wheel and for maintaining the contact springs out 120 125 130

of engagement during another portion of the travel of said wheel.

3. In an impulse transmitter, a rotatable toothed wheel, a contact spring normally insulated from said wheel while at rest and in electrical contact therewith during a complete revolution thereof, a second contact spring with which the first contact spring is brought into and out of engagement by the 10 teeth of said wheel, an insulated roller carried by the second contact spring, a cam seg-

ment carried by said wheel for maintaining the contact springs in engagement during a portion of the travel of said wheel, and another cam segment carried by said wheel and 15 engaging said insulated roller during a portion of the travel of said wheel for maintaining said contact springs out of engagement.

In witness whereof I hereunto subscribe my name this 9th day of May, A. D. 1916.

JOSEPH C. FIELD.
